UNITED STATES PATENT OFFICE.

CHARLES GRAHAM, OF BROOKLYN, NEW YORK.

DESIGN FOR A STATIONARY-TUB SUPPORT.

SPECIFICATION forming part of Design No. 22,316, dated March 28, 1893.

Application filed December 7, 1892. Serial No. 454,396. Term of patent 14 years.

To all whom it may concern:

Be it known that I, CHARLES GRAHAM, a citizen of the United States, residing at Brooklyn, in the county of Kings and State of New York, have invented and produced a new and original Design for Supports for Stationary Tubs, of which the following is a specification, reference being had to the accompanying drawing, showing the same in perspective.

10 The leading feature of my design consists in an arch with uprights having gracefully spread or flowing feet, and foliate scroll at the front. These are surmounted by the usual straight bar, the rear end of which is supported

15 by a straight upright. A bar reaches farther up from the front at the required inclination,

having a plane rib on each edge and a series of over-lapping scalloped ornaments up and down the center, formed in scrolls at the top and a loop at the bottom. A rib extends 20 upward from the junction of the feet at the base of the front upright, and sweeping over the arch gradually approaches the inner edge and flows into it. The rear upright has a straight rib at its back edge. 25

What I claim is—

The design for stationary tub support as herein shown and described.

CHAS. GRAHAM.
